(57) **CLAIM**

The ornamental design for a shoe, as shown and described.

DESCRIPTION

1. Shoe

1.1 is a perspective view of a shoe showing our new design;
1.2 is a front view thereof;
1.3 is a rear view thereof;
1.4 is a side view thereof;
1.5 is an opposite side view thereof;
1.6 is a top view thereof; and
1.7 is a bottom view thereof.

The various views of the design show only the right shoe; the right shoe is not shown as it is symmetrical to the left one.
